Primary Examiner — Rebecca Tsehay

(57) **CLAIM**

The ornamental design for a cigar rest, as shown and described.

DESCRIPTION

FIG. 1 is a top front perspective view of a cigar rest, showing my new design;

FIG. 2 is a front elevation view thereof, with the rear elevation view being a mirror image thereof;

FIG. 3 is a right elevation view thereof, with the left elevation view being a mirror image thereof;

FIG. 4 is a top plan view thereof; and,

FIG. 5 is a bottom plan view thereof.

The broken lines shown in the drawings depict a portion of the article that forms no part of the claimed design.
